WILLIAM D. POMEROY, OF SENECA FALLS, NEW YORK, ASSIGNOR TO GOULD PUMPS, INC., OF SENECA FALLS, NEW YORK, A CORPORATION OF NEW YORK

CAR-WASHING APPARATUS

Application filed February 6, 1928. Serial No. 252,389.

This invention relates to certain new and useful improvements in washing apparatus, and more specifically to an apparatus for spraying fluid upon automobiles, altho capable of use for various and many purposes.

The apparatus disclosed in this application is in a number of respects similar to the apparatus disclosed in my co-pending application filed July 27, 1927, Serial No. 208,807.

- 10 In car washers or outfits for spraying fluid upon cars or for other similar purposes, high pressures, as for instance 300 pounds, are required, and it is found that no ordinary spray outfit is capable of standing up very long 55
 15 under the strain of such pressures, or of satisfactory use in producing the result sought.

Further, it is quite essential that the pressure should be maintained substantially uniform at the desired point, irrespective of 60
 20 whether the spraying device or devices are being used or not, and that so far as possible, extreme pressure surges should be avoided in the system.

Further, in prior devices, it has been customary to use a pump from which the volume discharge is quite uniform, varying not more 65
 25 than about 22 percent during each cycle of movement, and with such a pump the operation of the regulator valve used has been unsatisfactory for the reason that with a pump having a very uniform discharge, the regulator valve will rise slightly off its seat when the required pressure exists in the system and will permit a portion of the discharge from 70
 30 the pump to continuously by-pass back to the intake of the pump and a condition of substantial equilibrium will exist in the system.

This continuous by-passing of a portion of the fluid from the pump gives a very high 75
 40 velocity discharge between the regulator valve and its seat, which cuts out the valve and its seat very rapidly, and further, the full load is maintained on the motor driving the pump, with the result that excess power 80
 45 has been used and the operative life of the apparatus has been brief.

I have discovered that by the use of a single cylinder double acting pump in which the volume of discharge varies substantially during 85
 50 each cycle, as for instance a variation

ranging from zero to 132 percent, that a regulator valve can be constructed for use with such a pump which will open suddenly and fully taking the entire discharge from the pump and relieving most of the pressure in 55
 the system and permitting the pump to merely circulate the fluid until such time as the pressure conditions controlling the regulator valve change to permit sudden and complete closing of such valve. It is found that in 60
 the use of a structure in which the suction side of the pump is connected, as for instance to a city water supply under a pressure of perhaps 50 lbs. and the pump discharges into a discharge air chamber to which the discharge nozzles are connected that the air in the discharge air chamber or other air chamber as used disappears until such chamber or chambers are practically full of water. Under 65
 this water logged condition there occurs 70
 very vicious hammering and pounding in the pump and the main object of this invention is to provide an efficient and automatic means for supplying air to the air chamber or chambers so as to maintain the maximum amount 75
 of air in said chamber or chambers, and to take this air at available pressures and step up the pressure in the pumping system itself.

A further object resides in the provision of a structure in which the regulator valve cuts 80
 in and cuts out at comparatively infrequent intervals so that the apparatus will not chatter itself to pieces during a comparatively short period of use.

A further object and advantage resides in 85
 the provision of a regulator cushioning chamber preferably adjacent the pump to substantially eliminate excess pressure conditions resulting in the system from rapid acceleration of fluid when the by-pass valves closes suddenly, and to cushion the operation of said valve.

The combination of elements at present deemed essential to accomplish the advantages above described, and other advantages 90
 that will hereinafter appear from the following description, involves preferably a single cylinder double-acting pump discharging 95
 into an air chamber having very considerable capacity as compared to the discharge of the 100

5 pump per cycle with a check valve to prevent flow of fluid back into the pump cylinder combined with a by-pass and valve controlling the same so proportioned as to open suddenly and fully, taking the entire discharge of the pump, and at the same time relieving most of the pressure in the system back of the check valve controlling the discharge air or cushioning chamber, and an auxiliary air 10 chamber for cushioning the operation of the regulator valve and for taking care of any excess pressure conditions that would result from sudden closing of the regulator valve all in connection with an outside source of 15 air pressure, as for instance the compressed air system ordinarily found in a garage or automobile workshop and from which source air is automatically supplied to the discharge air chamber to maintain maximum volume of 20 air in said chamber.

Other objects and advantages relate to the details of the structure; and the form, relation and association of the parts thereof, all as will more fully appear from the following 25 description, taken in connection with the accompanying drawings in which:

Figure 1 is an elevation, partially in section, of my apparatus taken on the line 1—1 of Figure 3.

30 Figure 2 is a section on line 2—2 of Figure 1.

Figure 3 is a section taken on line 3—3 of Figure 1.

Figures 4 and 5 are diagrammatic views 35 showing different levels of liquid in the apparatus under different conditions of operation.

The apparatus as here illustrated comprises a single cylinder double-acting pump, 40 perhaps best shown and illustrated in Figure 3. The cylinder —1— of this pump opens at opposite ends into the water ways or pump chambers —2— and —3— respectively, each of these chambers being provided with an inlet valve —4— and an outlet valve —5—. These valves may be of the composition disk type, and are normally held to their seats by springs, as shown, the springs being properly tensioned to effect the desired function.

55 The inlet pipe or conduit —6— (see Figure 1) which may be connected to any suitable source of fluid, as for instance, a water main, discharges into the inlet manifold —7— for supplying fluid thru the passageways controlled by valves —4— to the respective water-ways or chambers —2— and —3—, and upon the pressure strokes of the piston —8— mounted in cylinder —1—, the fluid is alternately forced under pressure through 60 the passageways controlled by the outlet valves —5— into an outlet manifold —9— connected by pipe or conduit —10— Figure 1 leading through a passageway —11— to the base of a discharge cushioning or air chamber —12— through a passageway —13— controlled

65 by valve —14— normally held by spring —15— to its seat, and operating to prevent the return of fluid from the discharge air chamber —12— to the outlet side of the pump.

The discharge air-chamber —12— is of very 70 considerable capacity as compared with the capacity of the pump per cycle of operation, and it is desirable to maintain a considerable air volume in the chamber —12— to effect the desired cushioning result, and for that purpose 75 a device is provided which will be herein-after described. The piston —8—, Figure 3, is reciprocated through the medium of a piston rod —19— extending outwardly through a stuffing box —20— and gland —21— secured there- 80 to, the stuffing box and gland forming a fluid-tight joint to prevent the escape of fluid from the pump along the piston-rod —19—.

A yoke —22— is secured to the outer end of the piston rod and is connected at its opposite ends to side rods (not shown) disposed upon opposite sides of the pump and extending substantially parallel with the piston rod —19—, the opposite ends of these side rods connected respectively to a cross-head consisting 90 of the parts numbered —25—, —26—, and the part —26— being guided in cylinder —27—, such cross-head being actuated by a connecting rod —28— mounted upon a bearing —29— eccentric with respect to gear —30— for reciprocating 95 piston —26— as the gear is rotated.

Gear —30— may be driven from a smaller gear —31— which in turn is driven from any convenient source of power.

It will be apparent that as the cross-head 100 is actuated, the piston —8— will be reciprocated by movement of parts described to alternately draw in and expel fluid to and from the respective water-ways or chambers —2— and —3—, and that the fluid under pressure 105 will pass from the manifold —9— by the opening of valve —14— into the discharge cushioning chamber —12— to produce the desired pressure.

In order that such pressure may be maintained under varying conditions of discharge from the chamber —12— through tubes or hose connections —37—, Figure 1, connected to pipe —38— and in order that continuous operation of the pump will not produce an excess pressure in the system beyond that desired, a regulator is provided adapted to be actuated by and in accordance with the pressure existing in the cushioning chamber —12—, and this regulator includes a chamber —41— connected as by pipe —42— to the lower portion of the discharge cushioning chamber —12— so that substantially the same pressure will exist in chamber —41— as exists in the chamber —12—.

One wall, as here shown, the upper wall of chamber —41— includes a flexible dia- 125 phragm —42— backed by a slid- 130 able member or piston —43—. A valve-operating rod —44— is connected to the piston —43— and at its upper end loosely engages a valve

—45— controlling the passage of fluid from the manifold —9— through pipe —46—, chamber —47—, to a pipe —48— leading, in this instance to the suction line —6— which returns the fluid to the manifold —7— of the pump.

When valve —45— is pushed upwardly from its seat so as to completely open the passageway from manifold —9— to pipe —48—, it will be apparent that the fluid may flow directly from the outlet or pressure side of the pump to the inlet or suction side of the pump, under which circumstances the pump is merely circulating the fluid without the production of any substantial pressure in the system.

Valve —45— is normally held to its seat by means of spring —49—, which spring is confined between the upper side of the valve 20 and the lower end of a regulator cushioning or air chamber —50—, which cushioning or air chamber is at all times in communication with the outlet side or manifold —9— of the pump. The piston —43— and valve 25 rod —44— are normally maintained in the position shown in Figure 1, (valve —45— being closed by spring —49—,) through the medium of a coil spring —51— confined between the upper surface of the piston 43 30 and the lower surface of a stop disk —52— secured in any suitable and preferably adjustable manner to properly tension the spring —51— as by means of bolts —53— secured to the wall of the chamber —41—, and 35 which chamber is supported as for instance by integral brackets —54—, depending from a casting which includes the chamber 47 and the passageway leading to the pipe —48—.

When the suction line —6— is connected 40 to a source of fluid under pressure, as for instance a city water line, a cushioning chamber —55— is provided which may be in the form of an elongated cylinder connected at its lower end by pipe —56— through check 45 valve 56' and pipe 6 to the manifold 7 to absorb shocks and to tend to maintain a uniform pressure in the fluid supplied to the inlet side of the pump.

The operation of the regulator of this apparatus will be understood from the following:

Valve 45 remains closed until a desired pressure is built up within the discharge cushioning chamber —12—. At that time the built-up pressure in chamber —12— also exists in chamber —41— and this pressure exerted upon the diaphragm —42— and piston —43— must be greater than the sum of the pressures of springs —49— and —51— plus 55 the pressure on top of the valve —45—, or else the valve would not open, and for that reason the pressure of the springs is so adjusted as to permit opening of valve —45— at the desired fluid pressure.

When sufficient pressure is built up in the

entire system so that the pressure in chamber —41— becomes great enough to overcome the forces opposing the opening of valve —45—, the valve —45— will be raised off its seat to a slight extent, and as soon as the operation of the pump reaches a point where substantially all discharge from the pump ceases momentarily, there is substantially no pressure on top of valve —45—, the check valve —14—, preventing the return of any pressure from chamber —12—, the valve —45— will snap wide open, due to the fact that under such circumstances the pressure in chamber —41— becomes substantially greater than the forces opposing it, and valve 70 —45— will remain wide open, permitting bypassing of substantially the entire capacity of the pump until pressure in air chamber 75 12 drops to such a point that the pressure in chamber 41 is less than the forces tending to close valve 45, at which time valve 45 will start to close.

If the pump used had a fairly constant discharge, it would tend to build up a condition of equilibrium in the system between the forces tending to open valve 45 and those tending to close it, and the valve would stay partially open, allowing a portion of the discharge from the pump to by-pass and a condition of equilibrium would be reached, but with the variable volume discharge pump here disclosed, it is apparent that at certain points in each cycle of operation, a very considerable extra volume of water is being discharged from the space between valve 45 and its seat, which will build up a momentary increased pressure on top of valve 45, and this increases the force tending to close valve 45 to such a point that the valve snaps closed 90 suddenly. The pump disclosed being a single cylinder double-acting pump delivers the water at an uneven rate. That is to say, there is a point in the operation of the pump where no water is being delivered. This is the point at which the cylinder changes its stroke. Between this point and the next change of stroke the water is delivered in an increasing amount up to the peak discharge and then the volume delivered falls off to nothing at the next change of stroke. Other types of pumps deliver the water in a more uniform amount through the cycle of their operations and it is, therefore, important in this type of apparatus that the type of pump herein described be used.

With sudden closing of the valve 45, an excess pressure condition would be built up in the system due to the fact that there is a considerable mass of stationary water in the pipes connecting between the pump and the air chamber 12, and this water would have to be very suddenly accelerated were it not for the provision of cushioning chamber 50, and the inclusion of such a regulator cushioning chamber is essential to the satisfac- 125 130

tory operation of the structure herein disclosed, and with a regulator valve operating as disclosed, and upon sudden closing of valve 45, injurious excess pressure conditions are not built up in the system for the reason that chamber 50 constitutes a space for receiving excess fluid, such space being made available by the compression of the air in chamber 50.

10 The by-pass valve 45 must be so proportioned that there is a proper relation between the forces tending to open the valve and those tending to close it when within the range in which it is desired to maintain pressure in the discharge air chamber 12.

15 It is not only desirable, but quite essential that the regulator valve shall operate at as infrequently intervals as possible, and the fact that the air chamber 12 is very large 20 as compared to the capacity of the pump per cycle has a substantial bearing on the frequency of operation of the regulator valve, and this for the reason that the greater the volume of air under compression in the air chamber, the longer will be the period of 25 charge or discharge of the air chamber with the maintenance of pressure within given limits.

30 In order that the apparatus shall function properly when initially started and shall continue so to function it is necessary that the chamber 12 be supplied with air and that the cushioning chambers 50 and 55 also be supplied with air as the machine is started 35 up. During the operation, the air which was initially placed in chamber 12 will gradually pass out from chamber 12 with the water as it is drawn off through the pipe 37. It is, therefore, necessary to provide a new supply of air to chamber 12 from time to time as the use of the apparatus 40 demands and it is, of course, preferable that this new supply of air be furnished automatically according to the needs of the apparatus.

45 To insure an additional air supply to chamber 12 and also to cushioning chamber 50, I provide a source of air under pressure (not shown) which air is brought to the apparatus through pipe 57, which pipe is connected through shut-off valve 58 to cushioning chamber 55 and through pipe 59, shut-off valve 60 and pipe 61 to the top of cushioning chamber 50. Pipe 61 is also connected to the upper portion of chamber 12. An auxiliary chamber 62 is connected at its lower end to pipe 48 which in turn, as heretofore described, is connected with suction line 6.

60 The air which is introduced through pipe 57 is ordinarily taken from the compressed air usually found in a garage or automobile workshop, which air is normally delivered at a pressure of approximately 100

70 lbs. per square inch. Pipe 61 carries at a point between shut off valve 60 and cushioning chamber 50 a restricted passage 64 for the purpose of controlling the passage of the compressed air through the pipe 61. The construction of restricted pipe 64, as perhaps may best be seen from Figure 2, consists of the incorporation into pipe 61 of a body 65 having an elongated aperture 66 of small diameter with a clean-cut plug 67 inserted therein. It will be understood that restricted passages similar to passage 66 which are very small in diameter are liable to become plugged from impurities which may be in the fluid passing through them and for this reason I provide the clean-out plug 67 which moves up and down in restricted passage 66 due to the fact that at times air is passing through restricted passage 66 while at other times it is not so passing through with the result that the movement of clean-out plug 67 will keep restricted passage 66 free from any obstruction. I also provide in pipe 61 between shut-off valve 60 and the upper end of cushioning chamber 50 two check valves 68 and 69 to prevent any air passing back from cushioning chamber 50 through pipes 61 and 59. When in the operation of my device the pressure of air in cushioning chamber 50 is greater than the compression of the air coming from the compressed air source. I also provide between the upper part of cushioning chamber 50 and chamber 12 another check valve 70 to prevent the passage of air from chamber 12 into cushioning chamber 50, when the pressure of the air in chamber 12 becomes greater than the pressure of the air in cushioning chamber 50. These valves 68, 69, and 70 are shown as of a common ball check valve type but it will be understood that check valves of other designs may be used if desired.

110 The operation of the automatic air supply portion of my device is as follows:

When the pump is started valves 58 and 60 are opened which will result in the passage of compressed air into chambers 12, 50, 55, and through leakage from chamber 55, into chamber 62. When these chambers are filled shut off valve 58 is shut since chamber 55 and 62 require no subsequent additional air. After the initial introduction of air, valve 60, on the other hand, is normally open and continues in that condition while the apparatus is being used.

115 After the pump has been running a sufficiently long time to introduce into chamber 12 a sufficient amount of water to bring the air in chamber 12 up to the selected and desired pressure, the level of water in cushioning chamber 50 will be approximately at a point indicated by line A-A on 120

Figure 1 leaving a certain amount of air between the water and pipe —61—. At the same time the level of the water in chamber —62— will be approximately at a point indicated by line A'—A' on Figure 1.

5 The pressure in chamber —12— having reached the desired maximum, valve —45— will be opened through the actuation of diaphragm —42— and rod —44—, as has been 10 previously described. When valve —45— has been opened, the bottom part of cushioning chamber —50— will be connected through pipe —48— with chamber —62—, and the pressure in cushioning chamber —50— will 15 be reduced to the pressure of the whole suction line, to which it and chamber —62— will be connected through the lower end of pipe —48—. Under this condition the suction side of the pump and the air chambers 20 —50— and —62— constitute practically a U-tube and the compressed air entering through pipe —57— and pipe —61— will force the water in cushioning chamber —50— downward to approximately the level shown by line 25 B—B on Figure 1. The forcing of the water level in cushioning chamber —50— downward will result in raising the water level in chamber —62— to approximately a line indicated by B'—B' on Figure 1 compressing 30 the air in chamber —62—.

When sufficient water has been removed from chamber —12— through pipe —37— to reduce the pressure in chamber —12— to a 35 point where valve —45— will again close as heretofore described, the water level in pipe —62— will return to the line A'—A' due to the fact that the pressure exerted upon it by the compressed air in cushioning chamber —50— has been cut off, and at the same 40 time the pressure on the lower end of cushioning chamber —50— will be increased to a point greater than the pressure in chamber —12— with the result that the water level in cushioning chamber —50— will move 45 upward to line A—A and the air which was introduced into cushioning chamber —50— will be forced through pipe —61— and check valve —70— into chamber —12—. It will be understood that valve —14— has an up- 50 per face of considerably greater area than its under face so that the pressure in the outlet manifold —9—, and the pipes —10—, —46— and cushioning chamber —50— will of necessity be greater than the pressure in chamber 55 —12— in order that valve —14— may be raised to permit the introduction of fluid through it from the pump into chamber 12.

In order that the functioning of chamber 50 may be understood (chamber 50 functioning as a cylinder with a fluid piston into which air is received at a comparatively low pressure and compressed to a much higher pressure and then delivered to chamber 12), I have shown diagrammatically in Figures 60 4 and 5 the approximate levels of fluid in

the different parts of the system under different conditions of operation.

In Figure 5 I show the levels of the fluid in chambers 12, 50 and 62 at a time when the valve 45 is open and the fluid is merely being 70 circulated through the pump and not forced forward into the bottom of chamber 12.

In Figure 4 I have shown the levels of liquid in the same chambers when valve 45 is closed and the fluid is being pumped into 75 chamber 12 through valve 14.

When the pressure in chamber —12— has been stepped up to a point where valve —45— has been opened, as previously described, the compressed air entering through pipe —57— and valve —69— will enter the top of chamber —50— and will force the fluid in chamber —50— down to approximately the level B—B shown on Figure 5. Inasmuch as the lower end of chamber —50— is connected through 80 valve 45 with the intake side of the pump, the pressure in which is considerably less than the pressure in pipe —57—, the lower end of chamber —50— being connected with the lower end of chamber —62—, the movement of 85 the fluid in chamber —50— downward will act on the fluid in chamber —62— forcing it upward to approximately a point shown by B'—B' on Figure 5 and thereby permitting 90 the reception into the top portion of chamber 95 —50— of a supply of air from pipe —57—.

At this time the pressure in chamber 12 is considerably higher than the pressure in chamber —50— but communication is cut off 100 between the two chambers by check valve —70—. Under these conditions the level of water in chamber 12 is approximately at a line shown by C—C on Figure 5. The levels of fluid in chambers —50— and —62—, just described, will continue unchanged until 105 sufficient fluid has been drawn off from chamber —12— through pipe —38— to lower the pressure in chamber —12— to a point where the valve 45 is again closed in a manner heretofore described.

When valve 45 has been closed, the levels 110 of liquid in chambers 12, 50 and 62 will be approximately as shown in Figure 4, the pump having built up a pressure on the outlet side which will be greater than the pressure in chamber —12— and the fluid will be delivered through valve 14 into chamber —12—. At the same time the pressure in the outlet side of the pump will be exerted on the fluid in chamber —50—. Since chamber —50— 115 has its lower end connected with the outlet side of the pump this pressure will cause the fluid in chamber —50— to move upward to a point approximately shown by line A—A on Figure 4 and inasmuch as check valve —69— will prevent the passage of air backward into pipe —57— the air on top of the fluid in chamber —50— will be compressed 120 to a higher degree than the pressure of the air in chamber —12— and will therefore be 125 130

forced through check valve —70— into chamber —12—. At the same time the fluid in chamber —62— will drop to approximately a level shown by line A—A' Figure 4 due to the fact that the pressure on it exerted by the fluid in chamber —50— has been removed by the closing of valve —45—. Part of the fluid in chamber —12— having been withdrawn through pipe —38— the level of fluid in that chamber will then be approximately on a line shown by D—D in Figure 4.

In other words, the chamber —50— with its fluid contents functions as a compressor in which the chamber walls comprise a cylinder, the fluid contents comprises a fluid piston which is moved upward on the compression stroke by means of the pressure in the outlet side of the pump when valve 45 is closed and which is allowed to move downward against the pressure of the air from pipe —57— when the pressure from the outlet side of the pump is reduced by the opening of the valve —45—. Check valve —69— functions as an intake valve of the compressor and check valve —70— functions as an exhaust valve of the compressor.

The levels of liquid shown in chamber —12—, 50 and 62 on Figures 4 and 5 and particularly those indicated for the level of fluid in chamber —12— are only approximate and are here used for the purpose of illustrating the functioning of the system because of the result desired will be obtained irrespective of the exact levels of liquid in the different parts of the apparatus. The balance between the amount of liquid and the amount of air in the cylinder —12— will vary under different conditions of service but under any conditions, during each cycle of operation a supply of air will be received from pipe —57— into the top of chamber —50— and will then be compressed and forced through valve —70— into chamber —12—. Furthermore, the rapidity with which the cycles of operation of my apparatus will occur will vary. In the event that chamber —12— is filled with a considerable amount of fluid, the cycle of operation will be comparatively rapid and a considerable amount of air will be delivered into chamber —12—. On the other hand, if the fluid level in chamber —12— is low, the cycle of operation will occur much less frequently with the result that a comparatively small amount of air will be delivered into chamber —12—.

For the purpose of explaining the operation of my device, I have described a single cylinder double-acting pump. However, the same result may be obtained with other types of pumps, as for example, a two cylinder single-acting pump with the cranks at 180 degrees so that I do not desire to restrict myself to any particular type of pump.

It will be understood also that the size of chamber —12—, cushioning chamber —50—,

and chamber —62— together with the size of restricted passage —66— may be varied to meet different conditions under which the apparatus is to be operated without departing from the spirit of my invention, and it will also be understood that various changes in the size and relation of the different individual units of my apparatus may be necessary due to variation in water pressure in the main supply line, to variations in the pressure in the air supply line and to variations in the demand which will be placed upon the apparatus in use, for although I have shown and described a specific arrangement and form of part as an exemplification of an embodiment of my invention, I do not desire to restrict myself to the exact shape, form or relation of parts as various changes may be made within the scope of the appended claims.

I claim:

1. In a device of the class described, a pump, a discharge air chamber in communication with the discharge side of the pump, a cushioning air chamber in communication with the discharge side of the pump, an auxiliary air chamber in communication with the suction side of the pump, means of communication between the cushioning air chamber and the auxiliary air chamber, a valve controlling such means of communication, and means for introducing air into the cushioning air chamber when the valve is open.

2. In a device of the class described, a pump, a discharge air chamber in communication with the discharge side of the pump, a cushioning air chamber in communication with the discharge side of the pump, an auxiliary air chamber in communication with the suction side of the pump, means of communication between the cushioning air chamber and the auxiliary air chamber, a valve controlling such means of communication, means for introducing air into the cushioning air chamber when the valve is open, and means for delivering air from the cushioning chamber to the discharge air chamber when the valve is closed.

3. An apparatus of the class described comprising a pump, a discharge air chamber having an inlet in communication with the pump, a valve controlling such communication, a cushioning air chamber in communication with the pump outlet, a connection between the said cushioning air chamber and the discharge air chamber permitting the delivery of air to the discharge air chamber from the cushioning air chamber by movement of fluid in the cushioning air chamber and means for supplying air under pressure to the cushioning air chamber.

4. An apparatus of the class described comprising a pump, a discharge air chamber having an inlet in communication with the pump,

- a valve controlling such communication, a cushioning air chamber in communication with the pump outlet, means for conveying air from the cushioning air chamber to the discharge air chamber when the pressure in the cushioning air chamber exceeds the pressure in the discharge air chamber and means for supplying air under pressure to the cushioning air chamber.
- 10 5. An apparatus of the class described comprising a pump, a discharge air chamber having an inlet in communication with the pump, a valve controlling such communication, a cushioning air chamber in communication with the pump outlet, means for conveying air from the cushioning air chamber to the discharge air chamber when the pressure in the cushioning air chamber exceeds the pressure in the discharge air chamber, means for supplying air under pressure to the cushioning air chamber when the pressure in the pumping system drops below an approximately predetermined point.
- 15 6. An apparatus of the class described comprising a pump, a discharge air chamber having an inlet in communication with the pump and having a capacity many times the volume of fluid discharged by the pump at each cycle of operation, a valve controlling such inlet, said discharge air chamber having an outlet separate from the said inlet, a by-pass conduit in communication with the pump outlet, a regulator valve controlling the passage of fluid through said conduit, means actuated in accordance with the pressure of fluid in the discharge air chamber for opening said regulator valve to permit by-passing of fluid, a cushioning air chamber in communication with said by-pass conduit at a point adjacent the pump and opening downwardly above the regulator valve, means for conveying air from the cushioning air chamber to the discharge air chamber when the pressure in the cushioning air chamber exceeds the pressure in the discharge air chamber.
- 20 7. An apparatus of the class described comprising a pump, a discharge air chamber having an inlet in communication with the pump and having a capacity many times the volume of fluid discharged by the pump at each cycle of operation, a valve controlling such inlet, said discharge air chamber having an outlet separate from the said inlet, a by-pass conduit in communication with the pump outlet, a regulator valve controlling the passage of fluid through said conduit, means actuated in accordance with the pressure of fluid in the discharge air chamber for opening said regulator valve to permit by-passing of fluid, a cushioning air chamber in communication with said by-pass conduit at a point adjacent the pump, and means for conveying air from the cushioning air chamber to the discharge air chamber when the pressure in the cushioning air chamber exceeds the pressure in the discharge air chamber.
- 25 8. An apparatus of the class described comprising a pump, a discharge air chamber having an inlet in communication with the pump and having a capacity many times the volume of fluid discharged by the pump at each cycle of operation, a valve controlling such inlet and said discharge air chamber having an outlet separate from the inlet, a valve controlling such outlet, a by-pass conduit in communication with the pump outlet, a regulator valve controlling the passage of fluid through said conduit, and means actuated in accordance with the pressure of fluid maintained in the discharge air chamber by said inlet and outlet valves for opening said regulator valve to permit by-passing of fluid, and a cushioning air chamber in communication with said conduit at a point adjacent the pump and opening into said by-pass conduit at a point adjacent the regulator valve, means for conveying air from the cushioning air chamber to the discharge air chamber when the pressure in the cushioning air chamber exceeds the pressure in the discharge air chamber.
- 30 9. An apparatus of the class described comprising a pump, a discharge air chamber having an inlet in communication with the pump and said chamber having a capacity many times the volume of fluid discharged by the pump at each cycle of operation, a valve controlling such inlet and said discharge air chamber having an outlet separate from the inlet, a valve controlling such outlet, a by-pass conduit in communication with the pump outlet, a regulator valve controlling the passage of fluid through said conduit, and means actuated in accordance with the pressure of fluid maintained in the discharge air chamber by said inlet and outlet valves for opening said regulator valve to permit by-passing of fluid, and a cushioning air chamber in communication with said conduit at a point adjacent the pump and opening into said by-pass conduit at a point adjacent the regulator valve, means for conveying air from the cushioning air chamber to the discharge air chamber when the pressure in the cushioning air chamber exceeds the pressure in the discharge air chamber.
- 35 10. An apparatus of the class described comprising a pump, a discharge air chamber having an inlet in communication with the pump and said chamber having a capacity many times the volume of fluid discharged by the pump at each cycle of operation, a valve controlling such inlet and said discharge air chamber having an outlet separate from the inlet, a valve controlling such outlet, a by-pass conduit in communication with the pump outlet, a regulator valve controlling the passage of fluid through said conduit, and a pressure chamber provided with a diaphragm, connections between said diaphragm and the regulator valve, and a conduit connecting the pressure chamber to the discharge air chamber.

air chamber at a point beyond the inlet valve of the latter, a cushioning air chamber in communication with said by-pass conduit at a point adjacent the pump, means for conveying air from the cushioning air chamber to the discharge air chamber when the pressure in the cushioning air chamber exceeds the pressure in the discharge air chamber.

11. An apparatus of the class described comprising a pump, a discharge air chamber in communication therewith, a valve controlling such communication, a regulator valve mechanism including a pressure chamber, means of communication between the pressure chamber and the discharge air chamber, a by-pass conduit in communication with the pump outlet, a regulator valve controlling the passage of fluid through said conduit, means actuated in accordance with the pressure in the pressure chamber for opening said regulator valve, and a cushioning air chamber in communication with said conduit at a point adjacent the pump and opening downwardly above the regulator valve, means for conveying air from the cushioning air chamber to the discharge air chamber when the pressure in the cushioning air chamber exceeds the pressure in the discharge air chamber.

12. An apparatus of the class described comprising a pump, a discharge air chamber having an inlet in communication with the pump and having a capacity many times the volume of fluid discharged by the pump at each cycle of operation, a valve controlling such inlet, said discharge air chamber having an outlet separate from the said inlet, a by-pass conduit in communication with the pump outlet, a regulator valve controlling the passage of fluid through said conduit, means actuated in accordance with the pressure of fluid in the discharge air chamber for opening said regulator valve to permit by-passing of fluid, a cushioning air chamber in communication with said by-pass conduit at a point adjacent the pump, means for conveying air from the cushioning air chamber to the discharge air chamber when the pressure in the cushioning air chamber exceeds the pressure in the discharge air chamber, and means for supplying air under pressure to the cushioning air chamber when the regulator valve is open and the pressure in the cushioning air chamber is comparatively low.

13. An apparatus of the class described comprising a single-cylinder double-acting pump, a discharge air chamber having an inlet in communication with the pump and having a capacity many times the volume of fluid discharged by the pump at each cycle of operation, a valve controlling such inlet, said discharge air chamber having an outlet separate from the said inlet, a by-pass conduit in communication with the pump outlet, a regulator valve controlling the passage of fluid through said conduit, means actuated

in accordance with the pressure of fluid in the discharge air chamber for opening said regulator valve to permit by-passing of fluid, and a cushioning air chamber in communication with said by-pass conduit at a point adjacent the pump, means for conveying air from the cushioning air chamber to the discharge air chamber when the pressure in the cushioning air chamber exceeds the pressure in the discharge air chamber, and means for supplying air under pressure to the cushioning air chamber when the regulator valve is open and the pressure in the cushioning air chamber is comparatively low.

14. An apparatus of the class described comprising a pump, a discharge air chamber having an inlet in communication with the pump and having a capacity many times the volume of fluid discharged by the pump at each cycle of operation, a valve controlling such inlet, said discharge air chamber having an outlet separate from the said inlet, a by-pass conduit in communication with the pump outlet, a regulator valve controlling the passage of fluid through said conduit, means actuated in accordance with the pressure of fluid in the discharge air chamber for opening said regulator valve to permit by-passing of fluid, a cushioning air chamber in communication with said by-pass conduit at a point adjacent the pump and opening downwardly above the regulator valve, means for conveying air from the cushioning air chamber to the discharge air chamber when the pressure in the cushioning air chamber exceeds the pressure in the discharge air chamber, and means for supplying air under pressure to the cushioning air chamber when the regulator valve is open and the pressure in the cushioning air chamber is comparatively low.

15. An apparatus of the class described comprising a pump, a discharge air chamber having an inlet in communication with the pump and said chamber having a capacity many times the volume of fluid discharged by the pump at each cycle of operation, a valve controlling such inlet and said discharge air chamber having an outlet separate from the inlet, a valve controlling such outlet, a by-pass conduit in communication with the pump outlet, a regulator valve controlling the passage of fluid through said conduit, and means actuated in accordance with the pressure of fluid maintained in the discharge air chamber by said inlet and outlet valves for opening said regulator valve to permit by-passing of fluid, and a cushioning air chamber in communication with said conduit at a point adjacent the pump and opening into said by-pass conduit at a point adjacent the regulator valve, means for conveying air from the cushioning air chamber to the discharge air chamber when the pressure in the cushioning air chamber exceeds the

pressure in the discharge air chamber, and means for supplying air under pressure to the cushioning air chamber when the regulator valve is open and the pressure in the cushioning air chamber is comparatively low.

16. An apparatus of the class described comprising a pump, a discharge air chamber having an inlet in communication with the pump and said chamber having a capacity many times the volume of fluid discharged by the pump at each cycle of operation, a valve controlling such inlet, and said discharge air chamber having an outlet separate from the inlet, a valve controlling such outlet, a by-pass conduit in communication with the pump outlet, a regulator valve controlling the passage of fluid through said conduit, a pressure chamber provided with a diaphragm, connections between said diaphragm and the regulator valve, and a conduit connecting the pressure chamber to the discharge air chamber at a point beyond the inlet valve of the latter, a cushioning air chamber in communication with said by-pass conduit at a point adjacent the pump, means for conveying air from the cushioning air chamber to the discharge air chamber when the pressure in the cushioning air chamber exceeds the pressure in the discharge air chamber, and means for supplying air under pressure to the cushioning air chamber when the regulator valve is open and the pressure in the cushioning air chamber is comparatively low.

17. An apparatus of the class described comprising a pump, a discharge air chamber in communication therewith, a valve controlling such communication, a regulator valve mechanism including a pressure chamber, means of communication between the pressure chamber and the discharge air chamber, a by-pass conduit in communication with the pump outlet, a regulator valve controlling the passage of fluid through said conduit, means actuated in accordance with the pressure in the pressure chamber for opening said regulator valve, and a cushioning air chamber in communication with said conduit at a point adjacent the pump and opening downwardly above the regulator valve, means for conveying air from the cushioning air chamber to the discharge air chamber when the pressure in the cushioning air chamber exceeds the pressure in the discharge air chamber, and means for supplying air under pressure to the cushioning air chamber when the regulator valve is open and the pressure in the cushioning air chamber is comparatively low.

18. In a device of the class described, a pump, a discharge air chamber in communication with the discharge side of the pump, a cushioning air chamber in communication with the discharge side of the pump, an aux-

iliary air chamber in communication with the suction side of the pump, means of communication between the cushioning air chamber and the auxiliary air chamber, a valve controlling such means of communication, means for introducing air into the cushioning air chamber when the valve is open, means for delivering air from the cushioning chamber to the discharge air chamber when the valve is closed, and means for preventing the movement of air from the discharge chamber to the cushioning chamber.

In witness whereof I have hereunto set my hand this 26th day of January, 1928.

WILLIAM D. POMEROY.
